UNITED STATES PATENT OFFICE

FRED E. FARLEY, OF GREENFIELD, MASSACHUSETTS, ASSIGNOR TO GOODELL-PRATT COMPANY, OF GREENFIELD, MASSACHUSETTS, A CORPORATION OF MASSACHUSETTS

BREAST DRILL

Application filed March 20, 1930. Serial No. 437,391.

This invention relates to breast drills of the change gear type and more particularly to an extremely simple construction that can be manufactured at low cost.

Various forms of breast drills provided with change gears for operating the drill at different speeds have been proposed heretofore, but most of the prior devices have been more or less expensive to manufacture. The present invention therefore relates to a simplified construction that can be manufactured at low cost and with a minimum number of machine operations.

One important feature of the present invention resides in a breast drill consisting of a spindle supporting frame that is slidably secured to the main post or stock for relative adjustment to mesh the different speed gears.

Another feature of the invention resides in the construction whereby the transversely extending shaft upon which the drive wheel or gear is journaled serves also to clamp the main post and frame in different positions of relative adjustment.

Still another feature of the invention resides in a breast drill in which the driving wheel or gear is connected to the main post while the rotating spindle having the bevel pinions and chuck is supported so that the post and driving wheel may be shifted together relative to the spindle to change the speed of the spindle.

Other features of the invention and novel combination of parts in addition to the above will be hereinafter described in connection with the accompanying drawings which illustrate one good practical form of the invention.

In the drawings:

Fig. 1, is a side elevation of a breast drill constructed in accordance with the present invention;

Fig. 2 is a sectional elevation taken at right angles to the elevation of Fig. 1; and

Fig. 3 is a side elevation of a bracket forming the intermediate portion of the breast drill.

The breast drill illustrated in the drawings has a post or stock 10 which may conveniently be formed of a round metal bar as shown and

the post 10 is provided at its upper end with a breast plate 11, which may be firmly secured to the post by a set screw 11^a. The lower end of the post 10 is slidably mounted in a sleeve 12 provided at the upper end of the bracket 13.

The bracket 13 preferably has the construction best shown in Fig. 3 and consists of the upper sleeve 12 and lower sleeve 14 which are supported in spaced relation to each other by the laterally spaced ribs 15, the construction being such that a clearance space is provided between the lower end of the sleeve 12 and the upper end of the sleeve 14 adapted to receive the bevel pinions to be described. The sleeve 12 is further provided with an elongated slot 16.

Within the lower sleeve 14 of the bracket 13 is rotatably mounted the spindle 17 adapted to support and rotate the chuck 18 which may be of the usual or any preferred construction. The spindle 17 is provided with the large and small bevel pinions 19 and 20, which are mounted on the spindle 17 to rotate within the clearance space of the frame 13 above mentioned. These two pinions are conveniently secured to the spindle 17 by a pin 21 extending through the spindle 17 and which lies in notches formed in the hubs of the pinions 19, 20. The construction is such that the pin 21 firmly secures the pinions to the spindle so as to prevent rotation therebetween while at the same time the engagement of the outer faces of the pinions with the inner ends of the spaced sleeves 12, 14 prevents longitudinal movement of the spindle 17 within the frame 13.

The means for rotating the spindle 17 and its chuck at different speeds consists of a driving wheel 22 having the large bevel gear 23 and the smaller bevel gear 24, and the driving wheel 22 is journaled upon a transversely extending bolt or shaft 25 which is provided at one end with the head 26 and at its opposite end with the threads 27. The bolt 25 is preferably provided with an enlarged portion 28 upon which the driving wheel 22 is journaled. In the construction shown the bolt 25 extends through a hole 29 formed adjacent the lower end of the post 10, the ar-

angement being such that when the parts so far described are assembled the post 10 may be slid lengthwise of the frame 13 the distance the transversely extending bolt 29 is permitted to move in the elongated clearance slot 16.

The relative movement just described between the post 10 and frame 13 serves to permit the high speed gears 19, 23 to be meshed as shown in Fig. 2 or the low speed gears 20, 24 to be meshed as shown in Fig. 1.

After the frame 13 and post 10 have been shifted relative to each other to engage the desired cooperating gears, the frame and post may be clamped in the desired position of adjustment by tightening the tool supporting handle 29, upon the bolt 25, the handle being provided to this end with the internally threaded sleeve 30. A washer 31 provided between the inner face of the driving wheel 22 and a side face of the frame 13 serves to keep this wheel properly spaced from the frame and the shoulder provided upon the bolt 25 at the inner end of the enlarged portion 28 engages the outer face of the washer 31 to receive the longitudinal thrust exerted upon the bolt 25 when the handle 29 is rotated to clamp the parts in the position in which they are shown in Fig. 1 or in the position in which they are shown in Fig. 2. Movement of the frame 13 relative to the post 10 after the parts have been clamped in the desired position of adjustment may be further prevented by providing the frame 13 with the lugs 32 adapted to cooperate with the washer 31 to prevent the latter from sliding upon the face of the frame. A washer 33 is preferably provided between the opposite face of the frame 13 and the inner end of the handle 29 as shown in Fig. 2. The driving wheel 22 may be rotated by the crank arm 34 provided at its outer end with the handle 35 and in the construction shown the inner end of the crank handle is notched so that it will fit the annular groove 36 formed in the hub of the driving wheel 22, and an intermediate portion of the crank 34 is secured to the driving wheel 22 by the screw 37.

It will be seen from the foregoing that the frame 13 constitutes the means for holding the post 10 and spindle 17 in axial alignment so that one may be shifted towards and from the other to engage the different gears. It will also be seen that the frame 13 rotatably supports the spindle 17 and through the cooperation of the pinions 19, 20 holds the spindle 17 against longitudinal movement within the frame. It will further be seen that when it is desired to shift the cooperating gears to vary the speed of the drill all that is necessary is to back off the handle 29 to permit the post 10 and driving wheel 22 connected thereto to be shifted lengthwise of the frame 13. It will be apparent from the foregoing description and drawings that the

breast drill of the present invention consists of a small number of parts, all of which are simple in construction and inexpensive to manufacture and that they are also strong and durable, thus making it possible to place the tool of the present invention upon the market at low cost.

While the features of the present invention have been shown and described in connection with a breast drill it is to be understood that the construction of the present invention is applicable to hand drills of the type that may be readily produced by providing the post 10 of the present breast drill with a handle at its upper end in place of the breast plate 11.

What is claimed is:

1. A breast drill comprising in combination, a rotating spindle carrying a chuck, a main post provided with means for rotatably supporting the spindle, a two speed drive for said spindle including a pair of pinions rigidly secured to the spindle and a driving wheel provided with a large bevel gear and a smaller bevel gear, and means for supporting said spindle for axial movement relative to said post to engage either of the gears with a pinion.

2. A breast drill comprising in combination, a main post, a frame slidably secured to said post, a spindle rotatably supported by the frame and provided with a chuck, a two speed drive for said spindle including a pair of pinions on the spindle and a driving wheel provided with a large bevel gear and a smaller bevel gear, and means whereby the post and frame may be relatively shifted to engage either of the gears with a pinion.

3. A breast drill comprising in combination, a main post, a rotating spindle provided with a chuck, a frame slidably secured to said post and constructed to rotatably support the spindle and to hold the post and spindle in axial alignment, a two speed drive for said spindle including a pair of pinions on the spindle and a driving wheel connected to the post and provided with a large bevel gear and a smaller bevel gear, and means whereby the frame may be secured in different positions of longitudinal adjustment relative to the post to engage either of the gears with a pinion.

4. A breast drill comprising in combination, a main post, a rotating spindle provided with a chuck, a frame slidably secured to said post and constructed to rotatably support the spindle and to hold the post and spindle in axial alignment, a two speed drive for said spindle including cooperating bevel gears and pinions, and means whereby the frame may be secured in different positions of longitudinal adjustment relative to the post to mesh different gears and pinions.

5. A breast drill comprising in combination, a main post, a frame slidably secured

to said post, a spindle rotatably supported by the frame and provided with a chuck, a two speed drive for said spindle including a pair of pinions on the spindle and a driving wheel provided with a large bevel gear and a smaller bevel gear, and means for connecting the driving wheel to the post to facilitate movement of the post and wheel relative to the frame to engage either of the 10 gears with a pinion.

6. A breast drill comprising in combination, a main post, a frame slidably secured to said post and provided with an elongated slot, a spindle rotatably supported by the 15 frame and provided with a chuck, a two speed drive for said spindle including a pair of pinions on the spindle and a driving wheel provided with a large bevel gear and a smaller bevel gear, a transversely extending shaft 20 for rotatably supporting said wheel and adapted to extend through said elongated slot and a portion of said post and operable to clamp the post and frame together in different positions of adjustment with the different pinions and gears meshed.

7. A breast drill comprising in combination, a main post, a frame slidably secured to the post, a spindle rotatably supported by the frame and provided with a chuck, a two 30 speed drive for said spindle including a pair of pinions on the spindle and a driving wheel provided with a large bevel gear and a smaller bevel gear, a transversely extending shaft for rotatably supporting said wheel and adapted 35 to clamp the frame and post together in different positions of longitudinal adjustments to thereby mesh the different gears and pinions.

8. A breast drill comprising in combination, a main post, a frame slidably secured to said post, a spindle rotatably supported by the frame and provided with a chuck, a two speed drive for said spindle including a pair of pinions on the spindle and a driving wheel 45 provided with a large bevel gear and a smaller bevel gear, and means for securing the post and frame in different positions of relative adjustment with the different gears and pinions meshed including a transversely 50 extending bolt and a handle threaded on the bolt to clamp it in different positions.

In testimony whereof, I have signed my name to this specification.

FRED E. FARLEY.
